UNITED STATES PATENT OFFICE.

JOSEPH E. SCHUMACHER, OF LOS ANGELES, CALIFORNIA.

PLASTER-BOARD.

1,268,802.

Specification of Letters Patent. Patented June 4, 1918.

Application filed March 16, 1917. Serial No. 155,233.

To all whom it may concern:

Be it known that I, JOSEPH E. SCHUMACHER, a citizen of the United States, residing at Los Angeles, in the county of Los Angeles and State of California, have invented a new and useful Improved Plaster-Board, of which the following is a specification.

This invention relates to an improved article of manufacture and method of producing the same, and more particularly to an improved plaster board or plaster lath and method of making same. The invention has for its object to provide an improved article of manufacture consisting of such plaster board or plaster lath, which will be superior in point of simplicity and inexpensiveness of construction and constitution, which will be superior in durability and length of life, and which at the same time may be employed more effectively in conjunction with a further wall element, such as a plaster coating, to support the latter.

The invention likewise has for further objects the provision of such improved plaster board or plaster lath as may be inexpensively produced and put into condition for service in conjunction with such further wall element, and likewise to provide a simple and efficacious method for the production of such article of manufacture.

With the above and other objects in view, the invention consists in the novel and useful formation and construction and organization of parts and features and the novel and efficacious method of producing the same, all as hereinafter described, shown in the drawing and finally pointed out in claims.

40 In the drawing:

Figure 1 is a fragmentary face view of a sheet or slab of plaster board or plaster lath constructed, constituted and produced in accordance with the present invention;

45 Fig. 2 is an enlarged detail sectional view of the same, taken upon the line x^2-x^2 , Fig. 1, and looking in the direction of the appended arrows;

Fig. 3 is an enlarged view of a sheet or 50 slab of such plaster board or plaster lath and of other instrumentalities utilized in forming and producing the same, or completing the same in the condition and formation shown in Figs. 1 and 2.

55 Fig. 4 is a working end or face view of the punch member or device shown in Fig. 3;

Fig. 5 is a view similar to Fig. 1, of a modified form of the invention; and

Fig. 6 is a view similar to Figs. 1 and 5, of a still further modified form of the invention.

Corresponding parts in all the figures are designated by the same reference characters.

Referring with particularity to the drawing, the improved plaster board or plaster lath is initially produced, in accordance with any preferred method or process, and comprises a body or filler *a* of cementitious or plastic material, which is disposed between face sheets *b* and *c* of paper or other suitable material which effectively confines and preserves the unity of the filler or body *a* during the setting or hardening thereof. Such a plaster board or plaster lath is well-known in the art, and the present invention relates particularly to certain features resulting upon or produced by modification or alteration of the continuous or imperforate formation of such plaster board or plaster lath sheet or slab, together with the method of procedure for producing such modification. It is understood of course that in order to perform the function of plaster lath, the article of manufacture comprising the filler or body *a* and the surface sheets or strips *b* and *c* must be provided with suitable irregularities of surface formation, or openings or holes or crevices or the like for the reception of the plastic or cementitious body, or further wall element, to be applied to such lath, so that an effective interlocking may result as between such further wall element and the lath. In accordance with the present invention, I provide through openings, 5, in the otherwise imperforate plaster board, such openings being preferably or at least effectively of constant transverse dimension, or cylindrical, such transverse holes or openings being conveniently and effectively produced by a suitable punch device *A*, as illustrated in Fig. 3, with which coöperate dies *B* and *C*. In practice, such dies are placed in facial contact with the plaster board article *D*, and one such die has a bore 6 to receive the punch 7 in approximately a working fit, whereas the bore 7 of the other die is of a materially increased diameter, the punch being first entered in the die *B*, and entering the die *C* after penetration of the plaster board article *D*. Such penetration is preferably produced by the joint use of the punch and the dies prior to

100

105

110

the placing the plaster board in position, so that the plaster board or plaster lath may be supplied in finished and completed form, ready to be installed and to receive the 5 plaster coating or other wall element to be applied to the same. The punch 7 makes a clean hole in its first penetration of the plaster board D, but as the punching operation proceeds toward the die C, which fails 10 to confine and support the plaster board closely up to the field of punching operation, but supports the main body of the plaster board laterally, or outwardly thereof, the penetrating pressure of the punch tends to 15 advance the material of the plaster board with the punch into the bore of the die C, or, in other words, to buckle the plaster board to the breaking point or to disrupt the same. Thus, while a clean cut is made 20 through the paper sheet c in facial contact with the die B, an increasing irregularity of puncture results in the plaster board body beyond such sheet, and toward the sheet b, the resultant of the penetrating action of the 25 punch and the buckling action of the plaster board producing an increasingly rough, mutilated, ragged and irregular inner wall of the bore produced by the punch, toward and through the sheet b, which latter sheet 30 is itself irregularly ruptured and developed into ragged and spaced tongues or ribbons, which initially are directed into the bore of the die C. Upon the withdrawal of the 35 punch 7 the roughened condition or formation, as at 8, persists in the inner walls of the through hole 5, and the slight inherent spring quality in the tongues 9 of the broken facial sheet b tends to restore the same to or toward the plane of the sheet b. The dies 40 B and C are now removed from the perforated plaster board, and a succeeding punching operation ensues to produce the plurality of through holes 5 indicated in Fig. 1.

45 If the punched or perforated plaster board sheets be stacked upon each other, as produced, there will be a tendency to restore the tongues or ribbons 9 of the paper b substantially to the plane of such paper sheet.

50 The plaster board D has now in effect been altered or modified so that it constitutes plaster lath, and is prepared to receive the plastic or cementitious further wall coating or element which may be applied to the 55 same in any suitable manner, and to the face thereof which is provided with the relatively clean-cut or perforated paper sheet or facial covering c. Such application of such plastic or mobile or mushy material 60 will result in penetration thereby of the holes or through openings 5, which will produce tongues or keys eventually hardening and setting within such openings to interlock the further wall element with the plaster lath and cause the same to be effectively

supported and retained thereby. As such penetration or protrusion of the plastic wall element occurs in the openings or holes 5, the material thereof will meet with partial obstruction by the rough, mutilated or altered formation of the body a, at 8, produced and described in the punching operation, and a material checking or retardation of such penetration or passage of the openings will be produced, preventing an overplus of such mushy or plastic material from passing through such openings and being wasted beyond or behind the lath. With the same effect, the tongues or ribbons 9 of the paper sheet b act in retardation or to check the passage of such wall material through such holes 5. A sufficient quantity of such material, however, protrudes through the holes 5 and between the tongues or ribbons 9, and over and beyond and past the 75 roughened or altered formation at 8, to produce a key or button beyond the surface sheet b, which, when hardened, positively and effectively, with its shank within the opening 5, prevents separation of the wall 80 coating or covering from the plaster lath; and such shank effectively interlocks with the roughened and altered or mutilated formation of the wall of the hole 5, adding to the efficiency of such interlocking action, 85 and inherent stability of the entire resultant wall structure, plaster-to-plaster or contacting engagement within these openings, of moist plaster with dry plaster, resulting likewise in a close adhesive joint within such 90 openings. All of these interlocking or inter-related actions serve far more effectively to unite the further wall element with the lath than would be the case if the holes 5 were perfectly cylindrical or had smooth 95 wall portions, or if the paper sheet b were cleanly punched through and the tongues or ribbons 9 not allowed to remain in position. The substance of the further wall element likewise surrounds and embeds to a 100 certain extent such tongues or ribbons 9, which likewise further acts as bonds to interlock such tongues with the plaster lath. The paper tongues or ribbons 9 will of course yield outwardly as the tongue or key 105 of wall material presses against the same, permitting such material to be projected beyond the plaster board; or, if the finished plaster board or plaster lath sheets are stacked up prior to use, and such tongues or 110 ribbons maintained substantially in the plane of the paper covering b, they will tend to re-assume the slightly outwardly-angled positions shown in Fig. 2, due to an inherent tendency in that direction caused 115 by the punching action. In any event, whether said tongues lie within the plane of the paper covering b, or are angled outwardly with respect to such plane, when the 120 wall material is applied to the lath, they 125

will serve somewhat to retard the intruding plaster key, as well as to unite with the same in bonding action.

As shown, punch 7 is provided with a 5 tapered end portion producing facets or end faces 10 separated by cutting edges 10^a; but it will be understood that any suitable working end formation of such punch may be employed.

10 A further coating of plaster or other material may be applied to the reverse side of the lath, the heads formed by the protruding plaster previously applied interlocking with said plaster coating and firmly supporting 15 the same. As shown in Fig. 5, an effective form of hole 5 comprises a triangular perforation producing tongues 9 which more closely overlap the hole and check the protruding plaster while yielding sufficiently 20 to permit the formation of heads for the purposes above described. As shown in the uppermost hole in Fig. 2, a suitable punch may be employed to cause mutilation of the first produced end of the hole on retraction 25 of such punch, for further interlocking purposes.

It is manifest that many variations in detail and in specific character may be made, in departure from the foregoing description 30 and statement and the showing of the drawing in adapting the invention, either with respect to the plaster lath itself or the method of its production, to varying conditions and requirements of use and service, all 35 without departing from the real characteristics of the invention and a fair interpretation of the spirit thereof.

Having thus disclosed my invention, I claim and desire to secure by Letters Patent: 40 1. As an improved article of manufacture, a plaster lath comprising a body of initially plastic material and facial sheets of flexible material between which such body is disposed; there being a plurality of through 45 openings produced through such sheets and said body and confined by roughened or mutilated walls; one of said surface coverings being disrupted in registration with each of said openings to produce irregular 50 tongues overlying the same.

2. As an improved article of manufacture, a plaster lath provided with perforations, said lath comprising a body and surface sheets between which the body is interposed; one of 55 said surface sheets being disrupted in the production of the perforations to provide tongues overlying one end of each perforation to partially and yieldingly seal the same.

3. Plaster board comprising surface sheets 60 of flexible material and a body of plastic material disposed between and uniting the sheets, one of the sheets and said body having registering openings and the other of

said sheets having openings therein registering with and being smaller than the openings of the first sheet and body, said last named openings having irregular confining walls.

4. Plaster board comprising surface sheets of flexible material and a body of plastic 70 material disposed between and uniting the sheets, one of the sheets and said body having registering openings and the other of said sheets having openings therein registering with and being smaller than the 75 openings of the first sheet and body, said last named openings having irregular confining walls, defining irregular tongues lying in approximately the same plane as the last named sheet. 80

5. An improved article of manufacture, a structurally completed plaster board comprising surface sheets united by a plastic body and having through openings formed therein, one of the surface sheets of said 85 board being formed to substantially and yieldingly close the openings at certain ends thereof.

6. A structurally completed plaster board having through openings provided therein 90 and one of its elements so formed as to materially and yieldingly retard the movement and the amount of wall material adapted to pass therethrough when the latter is applied to the board and extends into 95 and through the openings.

7. A structurally completed plaster board having through openings provided therein and one of its elements so formed as to materially retard the movement and the amount of wall material adapted to pass therethrough when the latter is applied to the board and extends into and through the openings; said element substantially and yieldingly closing one end of each of the openings.

8. A plaster board provided with through openings therein, and means for yieldingly holding certain ends of the openings closed and which act to open under the influence of plastic material applied to the board and which enters the openings.

9. A plaster board provided with through openings therein, and means for yieldingly holding certain ends of the openings closed and which acts to open under the influence of plastic material applied to the board and which enters the openings, said openings having irregularly confined walls.

In testimony whereof, I have signed my name to this specification in the presence of two subscribing witnesses.

JOSEPH E. SCHUMACHER.
